UNITED STATES PATENT OFFICE.

ALFRED P. HAYDEN AND FRANCIS PICKUP, OF BROOKLYN, NEW YORK.

CLAMP FOR SHEET-HOLDERS.

SPECIFICATION forming part of Letters Patent No. 292,307, dated January 22, 1884.

Application filed March 16, 1883. (No model.)

To all whom it may concern:

Be it known that we, ALFRED P. HAYDEN and FRANCIS PICKUP, both of Brooklyn, in the county of Kings and State of New York, 5 have invented a new and Improved Clamp for Sheet-Holders, of which the following is a full, clear, and exact description.

Our invention relates to improvements in clamps for sheet-holders; and it consists in the 10 peculiar construction and arrangement of the parts, as hereinafter more fully set forth, and pointed out in the claims.

Reference is to be had to the accompanying drawings, forming part of this specification, in 15 which similar letters of reference indicate corresponding parts in all the figures.

Figure 1 is a longitudinal view of the inside of a sheet-holder provided with our improved sheet-clamp, the holder being shown open. 20 Fig. 2 is a cross-sectional elevation of the same on the line *y y*, Fig. 1. Fig. 3 is an enlarged cross-sectional view on the line *x x*, Fig. 2.

Two covers, A, of pasteboard or analogous material, are united by a flexible back, B. On 25 the inner surface of the back B a metal strip or plate, C, is fastened parallel to the length of the back and parallel to the width of the covers, which plate is provided at its exposed surface with a longitudinal groove, D. On 30 one end of the plate or strip C a hook, E, is formed, and to the opposite end a jaw, F, is hinged, to which jaw a wire, G, is attached, which is provided at its free end with a head or button, H. The wire G has a downwardly- 35 bent part, J, between its ends, as shown. The wire G is of such thickness that it fits within the groove D. The strip or plate C can be attached to the cover instead of being fastened to the back B.

The operation is as follows: The backs are 40 swung apart and the wire G is raised, and one of the sheets, K, to be fastened or held to the covers, is placed on the plate C, and the wire G is pressed down, and its free end is pressed under the hook E, whereby the bent part J 45 will be pressed into the groove D, and will press the end of the sheet into the said groove, whereby the sheet will be held to the back. A single sheet or more sheets can be held in the manner described. If desired, the wire 50 can be hinged or otherwise fastened to a fixed jaw in place of being fastened to a hinged jaw.

This device is adapted for holding all kinds of loose sheets—for instance, express receipts, 55 check-blanks, note-blanks, &c.

Having thus described our invention, what we claim as new, and desire to secure by Letters Patent, is—

1. A sheet-holding clamp consisting of a 60 longitudinally-grooved plate or strip provided at one end with a hinged jaw, and a hook at the other end, combined with a wire, G, having a bent part, J, fitting in the groove of the plate or strip, substantially as described, and for the purpose set forth.

2. The combination, with two covers, united by a back, of the longitudinally-grooved strip or plate C, attached to the inner surface of the back, the hook E at one end of the strip, the hinged jaw F at the other end of the strip, 70 and the wire G, attached to the hinged jaw F, substantially as herein shown and described, and for the purpose set forth.

ALFRED P. HAYDEN.
FRANCIS PICKUP.
